UNITED STATES PATENT OFFICE.

JACOB A. TOSSOUNIAN, OF PHILADELPHIA, PENNSYLVANIA.

METALLIC TIE.

1,209,078.

Specification of Letters Patent. Patented Dec. 19, 1916.

Application filed August 2, 1916. Serial No. 112,880.

To all whom it may concern:

Be it known that I, JACOB A. TOSSOUNIAN, a subject of the Sultan of Turkey, residing at Philadelphia, in the county of Philadelphia and State of Pennsylvania, have invented new and useful Improvements in Metallic Ties, of which the following is a specification.

This invention relates to improvements in the construction of metallic ties for railway rails.

In carrying out my invention it is my purpose to construct a metallic tie of a simple design which, when arranged in the roadbed, will be self-sustained, that is will so engage with the roadbed as to prevent the movement of the tie in any direction except in a limited vertical direction.

It is also my purpose to construct a metallic tie having a hollow substantially rectangular body member and having its ends widened whereby to offer a greater contacting surface to the roadbed so as to insure the proper arrangement of the tie thereon against movement in any direction when embedded in the said roadbed and to further embed in the roadbed blocks or piles arranged to be received by the widened ends of the tie, each of the said blocks having a depression to receive one end of a helical spring, the other end of the said spring contacting with the upper portion of the tie, whereby a desired amount of resiliency will be afforded by the tie to the rolling stock passing over the rails secured to the tie.

It is a still further object of the invention to produce a metallic tie which shall embody the desirable features of simplicity, cheapness and thorough efficiency.

With the above and other objects in view the improvement resides in the construction, combination and arrangement of parts set forth in the following specification and falling within the scope of the appended claim.

In the drawing: Figure 1 is a top plan view of a tie constructed in accordance with the present invention and showing the rails secured thereon, Fig. 2 is a central longitudinal sectional view through the ties approximately on the line 2-2 of Fig. 1, Fig. 3 is a transverse sectional view approximately on the line 3-3 of Fig. 1, Fig. 4 is a greatly enlarged sectional view approxi-

mately on the line 4-4 of Fig. 1, and Fig. 5 is a perspective view of a portion of the tie. 55

My improved metallic tie may be cast or molded to produce a flat top surface 1 which at a suitable distance from its ends, is widened to its said ends but being inclined outwardly from its edges to its ends as 60 clearly disclosed in Figs. 1 and 5 of the drawings. The widened angular portions at the ends of the ties are indicated by the numerals 2, and the outer edges of the said angular portions are arranged at a right 65 angle to the body of the tie proper. The top, as well as its widened portions 2 are formed with a continuous flange 3 which, of course, is downturned and which is inclined outwardly from the said top as clearly disclosed in Figs. 1 and 3 of the drawings. The tie, at a suitable distance from the ends thereof, is provided upon its top with in-turned members 4 that are in staggered relation to each other and which are formed 75 with threaded bores to receive the threaded shanks 5 of headed members 6 and the heads of these members 6 contact with and partially overlie the base flanges of the rails 7.

In the roadbed, I embed suitable blocks 8 which may be of any desired material, preferably reinforced concrete or the like, the said blocks being in the nature of piers having their upper flat surfaces disposed a slight distance above the upper surface of 85 the roadbed proper and each of the blocks 8 has its said upper surface centrally provided with a rounded depression or pocket 9 to receive one end of a spring 10, the opposite end of each of said springs 10 encircling a 90 lug 11 provided upon the upper plate 1 of the tie. It will be noted that the blocks 8 and the springs 10 are disposed below the widened portions 2 of the top plate 1, and that the said blocks are inclosed by the 95 flange of the tie. The angular flange 3 is adapted to have the roadbed tamped there-around and the enlarged or widened portions of the flange formed with the widened portions of the top 2 and the angular arrangement or disposition thereof when engaged by the tamped roadbed will effectively prevent the movement of the tie longitudinally, and the peculiar arrangement of the flange upon the body of the tie as well as 100 upon the ends of the said tie will effectively

prevent the tilting, turning or lateral movement of the tie. The springs 10 will afford the tie the desired amount of resiliency so that danger of breakage of the rails or of the tie by the impact of force of the wheels of the rolling stock imparted thereto will be effectively overcome.

From the above description, taken in connection with the accompanying drawing, the 10 simplicity of the device, as well as the advantages thereof will, it is thought, be perfectly apparent to those skilled in the art to which such invention appertains without further detailed description.

Copies of this patent may be obtained for five cents each, by addressing the "Commissioner of Patents, Washington, D. C."

Having thus described the invention, what 15 I claim is:

In a railroad construction, blocks embedded in the roadbed and having their upper faces provided with pockets, a hollow tie arranged over the blocks and having its 20 outer surface engaged by the roadbed, lugs depending from the top plate of the tie disposed over the openings in the blocks, and spring members having one end within the openings and the other end surrounding the 25 lugs.

In testimony whereof I affix my signature.
JACOB A. TOSSOUNIAN.
